UNITED STATES PATENT OFFICE.

FREDERICK JAMES THODY, OF SWIFT CURRENT, SASKATCHEWAN, CANADA.

SHEAF SHOCKER.

Application filed October 19, 1920. Serial No. 417,952.

To all whom it may concern:

Be it known that I, FREDERICK JAMES THODY, a subject of the King of Great Britain, a resident of the town of Swift Current, Province of Saskatchewan, Dominion of Canada, have invented certain new and useful Improvements in Sheaf Shockers, of which the following is a specification.

This invention relates to improvements in sheaf shockers of the type in which the sheaves are received from the binder deck by a suitable transferring member which deposits them in a shock forming member, which is caused at suitable intervals to form the shock and deposit it upon the ground, and the general object of the invention is to provide a device of the character in which the desired operation may be efficiently carried out.

Other objects of the invention are to provide an effective device of this character, by which the shock may be formed from the discharged sheaves and deposited upon the ground in proper upright position and compressed together to form a stable shock.

Further general objects are to co-ordinate the functions required of the various parts in such a way that the sheaves will be received from the binder, transferred and deposited as a shock without interruption through mechanical difficulties or the like.

Particular objects of the invention relate to the transferring member and to the mechanism by which it is caused to receive the sheaves and deposit them in the sheaf shocking member.

Other particular objects of the invention relate to the mechanism for supporting and operating the shock forming member, and have for their object the proper compression of the sheaves, the lowering of the shock forming member in a substantially vertical position, the moving of the shock forming member rearwardly as it is depositing a shock, and gradually raising the shock forming member to return it to normal position.

Other objects of the invention will appear as the specification proceeds.

The invention comprises the improved construction, combination and arrangement of parts hereinafter described in detail in

the accompanying specification and drawings.

In the drawings:

Figure 1 is an elevation taken from the rear side of the machine.

Figure 2 is an elevation of one side of the mechanism. Figure 2^a is a sectional detail of certain of the parts shown in Fig. 2.

Figure 3 is an elevation taken from the opposite side of Figure 2 and being the side adjacent to the binder.

Figure 4 is an elevation taken from the forward side.

Figure 5 is a plan view.

Figure 6 is a sectional detail through the returning spring for the transferring member.

Figure 7 is a perspective detail of the rod supporting the rear closing door.

Figure 8 is a detail in plan of the said rod as shown in Figure 7.

Figure 9 is a perspective view showing details of the supporting means for the shock forming mechanism.

Figure 10 is a sectional detail of the supporting roller of the frame of the shock forming mechanism.

Figure 11 is a sectional detail through the bracket on the upper part of the supporting means for the shock forming mechanism. Figure 11^a is a sectional detail showing certain of the parts shown in Fig. 11.

Figure 12 is a vertical section detail through a portion of the operating mechanism for the shock forming mechanism.

Figure 13 is a perspective detail of the trip mechanism controlling the movement of the transferring member.

Figure 14 is a detail in elevation of the driving gear for the mechanism shown in Figure 13.

Figure 15 is a sectional detail through a portion of the mechanism shown in Figures 13 and 14.

Figure 16 is a perspective detail of the trip mechanism which is operated by initial movement of the shock forming mechanism.

Figure 17 is a sectional detail through a portion of the mechanism shown in Figure 16 taken on the line 17—17, Figure 16.

Figure 18 is another sectional detail through the mechanism shown in Figure 17

and taken at right angles thereto taken on the line 18—18, Figure 16.

Figure 19 is a perspective view of the clutch controlling the shock forming mechanism.

Figure 21 is a perspective detail of the 10 trip mechanism for the transferring means.

Figure 22 is a perspective detail of certain of the trip levers on the transferring mechanism.

Figure 23 is a detail in plan of the 15 releasing trip for the shock forming basket.

Figure 24 is a side view of the mechanism shown in Figure 23.

Figure 25 is a perspective detail of the 20 abutment member for returning the transferring basket.

Figure 26 is a detail of one of the dogs of the mechanism shown in Figure 23.

Figure 27 is a perspective view of the cradle.

25 Like characters of reference indicate like parts in all the figures.

Referring to the drawings; A represents a binder of any well known construction and B the binder deck thereof, including the 30 usual pivoted arm 10 which temporarily holds the grain prior to its discharge in the form of a sheaf. The arm 10 is turned in accordance with the usual mechanism of the binder about a transversely extending rod 11. 35 C indicates the frame carrying the shocking mechanism and which may be of any convenient construction to support the working part being connected at one side to the binder frame and supported at the other 40 side by a wheel D.

In the embodiment illustrated the connection with the binder frame is made by means of diagonally extending cross bars 12 and 45 13, the projecting extremities of which have hinged connection with the frame of the binder.

It is obvious however, that the mechanism might be attached to the binder frame in a variety of ways, or might be mounted independently on wheels of its own.

E indicates the transferring member by which the individual sheaves are transferred to the shock forming member F.

The transferring member E includes a 55 basket 14, the edge of which is normally adjacent to the edge of the binder deck and adapted to receive sheaves as they are discharged therefrom.

The basket is mounted with freedom to 60 turn about an axis somewhat inclined to the horizontal, whereby when swung upwardly from its normal position it will ultimately dump or discharge its sheaves into the shock forming member. This is accomplished by providing a supporting pivot

pin or trunnion 15 on an arm 16 of the frame C.

The pin 15 is embraced by a bracket 17, the arms 18 and 19 of which are connected to the extremities of the basket 14.

The sheave is retained in the basket 14, while it is being moved to proper dumping position by means of suitable pivotally mounted retaining fingers 20 which project from a rod 21 extending longitudinally of 75 the basket and are journalled in suitable bearing projections formed on a cross bar 22, which connects the arms 18 and 19 of the bracket 17. The fingers are retained in normal position by a toggle mechanism including rods 23 and 24 suitably pivoted together, the extremity of the rod 23 being pivoted to one of the fingers 20, while the extremity of the arm 24 is formed with an eye which embraces and pivotally supports 80 the arm from the pin or trunnion 15.

The normal position of the arms 23 and 24 is, as shown in Figure 3, where they are slightly inclined to each other and rest against an abutment 25 on the bracket 17.

When the transferring member is swung upwardly to the position shown in dotted lines in Figure 3, the joint of the toggle arms 23 and 24 is designed to be engaged by a tappet projection 26 on the frame member 16, which will swing the pivot point of the toggle arms away from the abutment 25, thereby permitting the arms to swing together and releasing the fingers so that the swinging fingers may swing downwardly 100 to release the sheaf which is in the basket 14.

On the return movement of the transferring member a spring 27 is designed to return the toggle arms 23 and 24 to their original position.

The transferring member as well as the shock forming member are operated from a transversely extending power shaft G driven in any convenient way, and is in the embodiment illustrated provided with a sprocket 28 connected by a chain 29 to the corresponding sprocket 30 carried by the wheel D.

The transferring member is operated from a toothed disc or ratchet wheel gear 31 on the power shaft, which is intermittently connected to the transferring member by the mechanism to be presently described. (See Figures 13, 14 and 15.)

This mechanism includes an arm 32 loosely and pivotally mounted on the shaft G and carrying a ratchet 33, the ratchet being in the form of an L-shaped arm having one portion journalled in the arm 32 and having a roller 34 on the extremity of the other portion designed to engage with one of the notches or teeth formed in the periphery of the disc 31. A dog 35 is connected to one end of the ratchet 33, having a flat spring 36 extending from one side thereof to a bracket

37 on the arm 32, the action of the spring through the dog being to normally hold the roller of the ratchet in engagement with the teeth of the disc 31.

5 The character of the teeth on the disc 31 is such, that when once the roller is thrown into engagement with the teeth, it will remain in engagement therewith.

10 The opposite end of the dog 35 to that connected to the spring is engaged by a hook-shaped end 38 of a trip dog 39, which is pivotally mounted on the arm 32 and is provided with a flat spring 40 extending from a bracket 41 on the arm 32 and designed to 15 hold the hook-shaped end of the dog 39 in engagement with the end of the dog 35. The dogs when in this relative position hold the ratchet 33 out of engagement with the disc 31. The dog 39 is designed to be tripped 20 at intervals by the laterally turned end 42 on a longitudinal slidable rod 43, which has the remote end formed with a hook 44 adapted to be engaged by the laterally turned end 45 on the vertically extending rod 46 suitably journalled in the frame and having a laterally turned lower end 47 pivotally connected to a rod 48, which rod is pivotally connected to a crank 49, the projecting end 50 of which is designed to be engaged by a 25 projecting arm 51 secured to the rod 11, and moving with the arm 10 already referred to.

30 A spring 52 is provided, holding the rod 46 in normal position and in which the end 45 is engaged with the end 44 holding the rod 43 in such position that the dogs 35 and 39 will be tripped.

35 A spring 53 extends between the rod 43 and the member 16 of the frame, normally holding the rod in position with the end 42 bearing against an abutment projection 54.

40 The hook-shaped end 44 on the rod 43 is supported on a spring section 55 which is welded or otherwise secured to the rod, or the rod itself is sufficiently thin at the end to be flexible, and the extreme end is provided with a tapered and laterally curved cam portion 56 designed to bear against the side of an eye 57 formed on a rod 58 pivotally mounted in the member 16, the lower end of the rod being formed with a turned end 59 which is held by a spring 60 against a laterally turned end 61 of a transversely extending rod 62, the opposite end of which is provided with a crank-shaped end 63 designed to be engaged and moved by a portion of the operating mechanism for the shock forming mechanism in the manner hereinafter described.

45 To give additional support to the arm 32, a bracket 64 may be provided secured to the side of the arm and embracing the shaft G. The arm 32 is pivotally connected at its extremity to one end of a rod 65, and the opposite end of the rod 65 is pivotally connected to the upper end of a rod 66, the op-

posite end of which is pivotally connected to the bracket arm 66^a at a distance away from the pivot point thereof. In normal position the rods 65 and 66 extend at an acute angle to each other, being held in this position by means of an abutment member 67 of inverted U-shape connected at its lower extremity to an arm 67^a of the bracket 17 and having its upper extremity curved and extending substantially at its pivotal point between the members 65 and 66. In this way, when a pull is exerted on the member 65, the member 67 will support the member 66 and cause the basket to be swung upwardly, finally as the revolution of the basket continues, the member 66 will swing out of engagement with the member 67 and thus permit a greater movement of the basket than would be possible if the member 65 were directly pivoted to the member 67.

50 In order to start the transferring member E on its return movement after a sheaf has been discharged, I provide a spring abutment member 68 (see Figure 6) which includes a cylinder 69 having a projecting plunger 70, the end of which plunger is designed at its extreme movement to engage an abutment projection 71, and this return movement is also assisted by gravity, too rapid a movement being prevented by means of a spring 72, which has one end connected to the member 16 and has the opposite end connected to a link 73, which is pivotally connected to an arm 74 on the bracket 17.

55 The operation of the trip device for the transferring member E above described is substantially as follows:

60 Upon discharge of a sheaf from the binder, the movement of the arm 10 in the automatic operation of the binder will move the arm 51, permitting the crank 50 to swing under action of the spring 52, which carries the rod 48 which turns the rod 46 about its vertical axis, and this, through the turned end 45 moves the rod 43 longitudinally and the turned end 42 of the last mentioned rod will engage the dog 39 swinging it about its pivotal point to release the dog 35, which under action of the spring 36 will move the ratchet 33 into engagement with the disc 31, thus causing the arm 32 to travel with the disc 31; the disc has previously been continuously rotating under the power derived from the wheel D through the power shaft G. The spring 52 also serves to restore the arm 46 to normal position.

65 The motion of the arm 32 through the rod 65 will swing the basket up towards raised position as indicated in dotted lines in Figure 3, the sheaf being released in this raised position and discharged into the shock forming member F.

70 Before the arm 32 has completed quite a half revolution, the end of the dog 35 is engaged by a tappet projection 75 which bears

it back into engagement with the hook-shaped end 38 releasing the ratchet 33 from the disc 31 and arresting the movement of the arm 32 permitting the basket freely to 5 return to normal position under the action of the spring plunger 70 and gravity as already explained. At the same time the spring 52 will return the rod 46 to normal position.

This excess motion is taken care of by the 10 tapered cam portion 56 of the rod 43, which bears against the projection 57, swinging the end laterally out of engagement with the end 45 enabling the end 45 to swing through a wider arc than would be necessary to move 15 the rod 43 to release the dogs. On the return movement of the end 45 it will slip past the projecting hook-shaped end and come into engagement with the notched portion 20 thereof, assuming the position shown in Figure 13 of the drawings.

To assist the holding of the basket 14 in normal position, a spring catch 76 is provided having a pair of fingers 77 and 78 designed to resiliently engage a projection 25 79 on the arm 18.

The shock forming member of the basket F includes a cradle H having pintles 80 and 81 journaled in suitable bearings 82 and 83 on arms 84 and 85 extending from one end 30 of the main supporting lever I for the shock forming mechanism.

This main supporting lever, (see Figures 9, 10, 11 and 12), is supported at the end remote from the shock forming member by a 35 roller 86, which runs in a guide-way 87 having an upper track 88 and a lower track 89. The roller is connected to the lever I by a shackle 90 pivotally connected to the pivot pin 91 of the roller on the lower end, and having its upper end embracing the U-shaped bale 92 connected to the extremity of the lever. The opposite end of the lever I to that which is supported by the roller 86, is supported by a pivoted bale or lever 93 of inverted U-shape, the upper extremity of the lever being embraced by a shackle 94 having a transverse pin 95 extending therethrough on which a bracket 96 is pivotally mounted having its opposite extremity embracing the 50 end of the lever I.

It will be seen that by the provision of this pivot pin 95, as well as by the pivoting of the shackle 94, the lever I is free to swing about these pivots under the action of gravity and so support the cradle in a horizontal position and thus deposit the shock in the position which will insure its maximum stability.

The lower extremity of the bale 93 is pivotally connected to a similarly shaped bale or lever 97, the upper extremity of which is supported from a bearing 98 connected to a cross bar 99 on the frame C.

The lower pivoted points of the bales 93 and 97 are normally retained in fixed posi-

tion by means of fixed stops 100 and 101, and movable stops 102 and 103, the latter being constituted by the extremities of a crank shaft 104 which is journaled in bearings 105 and 106 on cross bars 107 and 108 on the 70 frame, the said crank shaft being formed with a centre crank 109 having an offset arm 110 rigidly connected thereto from which a link rod 111 leads to a bell crank 112 journaled in a bearing 113 on the frame, the upper extremity of the bell crank being designed to be engaged and operated by a cam J as hereinafter described.

The crank 109 is retained in normal position by means of a flat spring 114 (see Figure 80 12), the spring being supported from a cross bar 115 on the frame.

The cradle H carries the shock forming basket which comprises a plurality of hinged sections 116, 117, 118, 119 and 120, the sections 116, 117 being pivoted together at the rear end by the pivot pin 121, the section 118 being hinged to the section 116, the section 119 being hinged to the section 117, while the section 120 is hinged to the section 116 and 90 designed to overlap the section 117 to avoid any opening in the bottom of the basket when open.

The sections 116, 117, 118, 119 and 120 are all supported from supporting links 122 and 123 rigidly connected to the sections 118 and 119 at one end and at the other to rods 124 and 125 on the cradle H. The position of the supporting links 122 and 123 are controlled by means of rods 126 and 127 pivoted at their upper extremities to cross rods 128 and 129 on the links 122 and 123 and pivoted together at their lower extremities. One of the rods is extended beyond the lower pivot point to form a connecting eye 130 which 100 connecting eye, when in raised position, is supported by a pivoted hook 131 gravity and spring held in engaged position and adapted to be released by a cord or chain 132 leading to the driver's seat on the binder.

It is obvious that the eye 130 might be formed separately if desired, and connected to the pivoting point of the rods.

It will be seen that when the pivoted hook or lever 131 is swung to released position the parts 116 and 117, 118, 119 and 120 are closed together under gravity brought about principally by weight of the sections 116 and 117, the inner sections being forced inwardly as they move downwardly by the links 122 and 123. The link 123 carries a hook-shaped projection 133, and as the section 119 is swung inwardly the projection 133 will engage with the crank shaped end 134 on a longitudinally extending rod 135 journaled in suitable bearings 136 and 137 on the arm 84 as shown in Figures 5, 16 and 27.

The opposite end of the rod 135 is formed with a crank 138 connected by a link 139 with a bell crank 140 mounted in a bearing 130

141 on the member 84, the opposite projecting end 142 of the bell crank lever being adapted to engage a laterally turned end 143 of a vertically extending rod 144 journalled in bearings 145 and 146 on the vertical bar 147 of the frame, Figs. 4 and 18.

The lower extremity of the rod 144 is provided with a crank 147^a designed to engage a flat pivoted dog 148 which has a turned end 149 extending across the end of a sleeve 150 which slidably holds the rod 151.

The dog 148 is conveniently pivoted to the side of the sleeve 150 and held normally in position by a spring 152 connected at one end to the dog and at the other end to the sleeve 150 which spring is adapted to return the rod to its normal position.

The rod 151 projects rearwardly and is pivotally connected to a bracket 154 on the cradle H and it is impossible for the cradle to be turned on its transverse pivot until the end 149 of the dog is swung away from the end of the sleeve 150, but when the dog is swung away from the end of the sleeve, the rod 151 may slide rearwardly permitting the cradle to turn on its pivot swinging the basket to vertical and discharging position.

The sleeve 150 is pivotally supported from a bracket 155 on a cross bar 156 of the frame, the bracket being pivotally connected to a corresponding bracket 157 which encircles the sleeve.

It will be noticed that the sleeve 150 is (see Figs. 2, 16, 17 and 18) of considerable length which permits the end of the rod 151 to run backwardly in it as hereinafter described,

To return the end 142 to normal position, a spiral spring 135^a is provided on a tie rod 135 extending between the rod and the bearing 137 and secured to each.

The turning movement of the cradle and basket to dumping position is assisted by means of tensioned springs 158 extending from lugs 160 on the cradle to levers 161 on the projecting ends of pintles 82 and 83.

The cradle H carries a tappet arm 163, which tappet arm is adapted as the cradle swings, to engage a laterally turned end 164 on a longitudinally extending rod 165 suitably journalled in the frame and having a laterally turned projecting inner end 166 as shown in Figs. 5 and 19. This laterally turned end 166 is connected by a link 167 with a centrally fulcrumed dog 168 mounted on a fixed standard 169 on the frame, the dog 168 normally holding a pawl 170 in disengaged position, this pawl being pivotally mounted on an arm 171 connected rigidly to a sleeve 172 which is loosely and pivotally mounted on the power shaft. The pawl 170 carries a roller 173 designed to engage one of a series of semi-circular recesses 174, which form teeth in the periphery of a disc or ratchet wheel 175 mounted

and turning with the power shaft G. The sleeve 172 also carries the operating cam J.

When the pawl 170 is moved into engagement with the teeth on the ratchet wheel 175, the arm 171 moves with it turning the cam J, which controls the movement of the roller 176 supported on a swinging arm 177, which arm is pivoted at its lower extremity to the frame.

The swinging arm 177 is pivotally connected to a rod 179 which extends rearwardly and is pivotally connected at its rear-most end to the shackle 94 at the top of the lever 93 connected to the lever I.

The first action of the cam is to permit the roller to drop inwardly on the radially extending portion 180 of the cam, the remaining travel of the cam being operative to hold the basket in position and then to gradually raise the cradle and basket and return them to normal position.

The cam carries on one side, a roller 181 and as the cam turns, this roller will engage between the forked ends 182 of a rod 183, the opposite end of which is pivotally connected to a bracket 184 on the bale or lever 97.

The cam J carries a second roller 185 on the opposite side to the roller 181 designed at a certain point of revolution to engage a cam surface 186 on a lever 187, which lever is pivoted to a second lever 188, the lower extremity of which is suitably journalled on the frame, and has an arm 189 which is connected by a tension spring 190 with the pivoted arm 177.

It will be seen that the lever 187 is free to both move on its pivotal point and to move rearwardly. The rearmost end of the lever 187 is pivotally connected to a rod 191 journalled in a suitable bearing 192 supported from the lever I, and its forward end is provided with a pulley 193 or other contact means designed to engage the outer surface of the connecting eye 130 to cause the opening of the basket through the arms 126 and 127.

To prevent the sheaves from falling out of the end of the basket until the proper position is reached, end doors 195 and 196 are provided supported by U-shaped bales 197 and 198, the extremities of which are pivotally mounted in projecting arms 199 extending from the arms 84 and 85. These doors are caused to swing outwardly and upwardly at the proper moment by curved bales 200 and 201 pivotally connected to the doors and having their opposite extremities connected by swivel or universal joints 202 to projecting brackets 203 on the links 122 and 123, details of this joint being given in Figures 7 and 8.

It will be seen that the end of each rod 200 extends through a sleeve 204 and is free to turn therein, the sleeve having an eye 205

formed thereon which fits through and turns in a suitable perforation in the bracket 203.

The operation of the shock forming mechanism is briefly as follows:

When a sufficient number of sheaves have been accumulated in the basket, the driver operates the cord 132 thereby swinging the hook 131 to disengage the eye 130 which permits the sections 116, 117, 118, 119 and 120 to close together, and at the same time move downwardly under gravity and under the action of the spring 158.

Shortly after this movement has commenced the member 133 engages with the end 134 of the rod 135, which through the connecting mechanism already described, operates the rod 144 to move the dog 148 permitting the rod 151 to move inwardly, and this in turn permits the cradle to turn on its pintles towards a discharging position in which the sheaves may be deposited on the ground in a vertical position.

Before this movement is completed however, the member 163 will engage the projecting end 164 of the rod 165, which will, through the mechanism already described, throw the pawl 170 into engagement with the continuously rotating disc 174 and cause the cam J to commence to turn.

Further movement of the roller 176 releases the cradle and permits the lever I to swing down, as already described. The roller 181 engaging the end 182 of the lever 183 will swing the lever or bale 97 backwardly which will permit the basket to drop substantially vertically.

The cam J continuing on its movement, the roller 185 thereof, will, through the mechanism already described including the lever 187, open the basket and permit the shock to disengage itself therefrom remaining on the ground.

When the lower pivoting points of the levers 93 and 97 are moved rearwardly after having been moved forwardly the stops 102 and 103 will be swung into normal position again and will finally become locked in position between the stops. After this takes place, the weight of the cradle will swing the lever 93 rearwardly through the lever 97 carrying the member I rearwardly. After the shock has left the basket, the basket is returned to its normal position by motion of the cam acting on the roller 176 as above described.

Any excess movement of the cradle is prevented by means of a flexible cord or cable 208 extending from the frame to the cradle.

On return movement of the cradle, the arms 84 and 85 are steadied by projecting arms 210 and 211 on the frame. The arms 210 and 211 are flexible and secured at one end to the main frame.

It will be seen that during the foregoing operation, the shock of sheaves is first compressed by the closing of the sections of the basket on them. The basket with its cradle is then turned to a vertical position and lowered, the doors closing the end of the basket being swung apart to permit the shock to be deposited on the ground. The basket and shock is thus lowered so that it will drop in a substantially vertical line and after the shock drops on the ground the basket moving backwardly remains with it momentarily until it is opened thereby giving proper form to the shock. The downward movement of the cone-shaped basket will cause a pressure to be exerted on the shock which will serve to press the sheaves together into a firm and proper shock.

After the shock has been deposited on the ground, the basket is opened and gradually raised and finally turned toward the horizontal and open position ready to receive the sheaves to form another shock. To relieve a portion of the weight of the basket and other mechanism, I provide a rope or cable 212 extending over a pulley 213 on the upright 214 having its opposite extremities connected by springs 215 and 216. It will be observed that the parts of the lever I are on opposite sides of the upright member 214 whereby the mechanism carried by the lever will counterbalance each other on opposite sides.

Retrograde movement of the cam J with respect to the roller 176, when the end movement of the cam is reached is prevented by a spring dog 217 on the cam which is pressed outwardly against a pin 218 by a spring 219 and is V-shaped and forms a ratchet for the roller 176, the roller being free to ride over the projecting end of the dog in one direction but not in the other.

Operation of the transferring mechanism during discharge of the shock is prevented by the end 63 of the lever 62 which becomes disengaged from the lever 93 against which it bears, thus permitting the lever 59 to turn under action of the spring 60, turning the end 57 which moves the hook-shaped end 56 of the rod 43 laterally, disengaging it from the end 45 and thus rendering inoperative the trip mechanism which would be normally operated by the means previously described, whenever a sheaf is discharged from the binder.

If the binder should discharge more than one sheaf during the time the shock forming mechanism is discharging, the additional sheaf will remain in the basket or transferring member and will be transferred with the next sheaf to the basket or shock forming mechanism when in proper position.

It will also be seen that by adjusting the relative length of the rod and shape of the cam, the tilting motion of the basket could

be enlarged, increased, or eliminated as desired to suit the character of crop or conditions of operation.

It will be observed that the mechanism above described causes the shock carrying basket to be raised slightly immediately after dropping to the lowermost position and during opening of the basket, whereby the basket will be clear of the ground when opened and during withdrawal from the shock, this action being caused to take place by the shape of the cam J.

In order to prevent the grain slipping lengthwise of the basket, a plurality of projections 220 are formed on both the transferring basket and the shock forming basket. The clutch mechanism is simple and effective, composed of few parts all well adapted to perform the functions required of them.

It will be observed that owing to the manner in which the collapsible basket is formed it automatically adjusts itself to different sized sheaves including short and long sheaves, the basket being formed with overlapping sections and being originally cone-shaped and closing in from the top will enable the parts of the basket to automatically adjust themselves to suit the character of grain of which the shock is to be formed.

As many changes could be made in the above construction and many widely different embodiments of my invention within the scope of the claims constructed without departing from the spirit or scope thereof, it is intended that all matter contained in the accompanying specification and drawings shall be interpreted as illustrative and not in a limiting sense.

What I claim as my invention is:

1. A sheaf shocker of the character described comprising a shock forming basket, means for discharging sheaves into the basket, means for closing, turning and lowering the basket to discharge the sheaves in the form of a shock, and means for opening the basket and raising the basket slightly during opening. 70

2. A sheaf shocker of the character described, comprising a collapsible shock forming basket, means for discharging the sheaves into the basket, and means for closing, turning and lowering the basket to discharge the sheaves in the form of a shock, and means for opening the basket, and raising the basket slightly during opening, and so means for returning the basket to normal position. 75

3. A sheaf shocker of the character described, comprising a frame, a pivotally mounted cradle, a supporting member for the cradle adapted to move forwardly and rearwardly, a collapsible basket supported from the cradle, a mechanism for operating the cradle to turn the same to discharge a shock, a mechanism for operating the basket to close the same on the sheaves to form a shock, to turn the basket and to open the same prior to discharging, and a mechanism for moving the supporting member rearwardly prior to discharge of the shock. 85 90

4. A sheaf shocker of the character described, comprising a frame, a pivotally mounted cradle, a supporting member for the cradle adapted to move forwardly and rearwardly, a collapsible basket supported from the cradle, a mechanism for operating the cradle to turn the same to discharge a shock, a mechanism for operating the basket to close the same on the sheaves to form a shock, to turn the basket and to open the same prior to discharging, a mechanism for moving the supporting member rearwardly prior to discharge of the shock, and means for lowering the cradle and basket. 95 100

5. A sheaf shocker of the character described, comprising a frame, a pivotally mounted cradle, a supporting member for the cradle adapted to move forwardly and rearwardly, a collapsible basket supported from the cradle, a mechanism for operating the cradle to turn the same to discharge a shock, a mechanism for operating the basket to close the same on the sheaves to form a shock, to turn the basket and to open the same prior to discharging, a mechanism for moving the supporting member rearwardly prior to discharge of the shock, means for lowering the cradle and basket, a supporting lever for the supporting member, and means for moving the supporting lever forwardly during lowering of the basket. 110 115 120 125

6. In a sheaf shocker and in combination, a supporting member, a lever pivotally supporting one end of the supporting member, means for supporting the opposite end 130

3. A sheaf shocker of the character de-

- of the supporting member with freedom to move forwardly and rearwardly, a shock forming basket carried by the supporting member, means for operating the same to 5 discharge the sheaves in the form of a shock, and means for moving the supporting member rearwardly.
9. In a sheaf shocker and in combination, a supporting member, a lever pivotally supporting one end of the supporting member, means for supporting the opposite end of the supporting member with freedom to move forwardly and rearwardly, a shock forming basket carried by the supporting member, means for operating the same to 10 discharge the sheaves in the form of a shock, means for moving the supporting member rearwardly, a supporting lever for the supporting member pivoted thereto and having its lower end movable, and means for moving the lower end forwardly prior to 15 discharge of the basket.
10. In a sheaf shocker and in combination, a supporting member, a lever pivotally connected at one end to the supporting member, a frame, a second lever pivotally connected at one end to the first mentioned lever, and pivotally connected at the other end to the frame, means for supporting the opposite 20 end of the supporting member to that connected to the lever with freedom to move forwardly and rearwardly, and a shock forming basket carried by the supporting member.
11. In a sheaf shocker and in combination, a frame, a supporting member, a guide-way, a roller in the guide way, means connecting the roller with one end of the supporting member, a lever pivoted to the frame, a second lever pivoted to the free end of the first mentioned lever and having its opposite end pivotally connected to the supporting member.
12. In a sheaf shocker and in combination, a frame, a supporting member, a guide-way, a roller in the guide-way, means connecting the roller with one end of the supporting member, a lever pivoted to the frame, a second lever pivoted to the free end of the first mentioned lever and having its opposite end 40 pivotally connected to the supporting member, and a releasable stop engaging the pivoted ends of the two levers.
13. In a sheaf shocker and in combination, a frame, a supporting member, a guide-way on the frame, a roller mounted in the guide-way, a shackle connecting one end of the supporting member to the roller, a U-shaped lever having the closed end pivotally mounted on the frame, a second U-shaped lever having its free end pivotally connected to the free end of the first mentioned U-shaped lever, and a shackle connecting the opposite 50 end of the second lever to the supporting member.
14. In a sheaf shocker and in combination, a frame, a supporting member, a guide-way on the frame, a roller mounted in the guide-way, a shackle connecting one end of the supporting member to the roller, a U-shaped lever having the closed end pivotally mounted on the frame, a second U-shaped lever having its free end pivotally connected to the free end of the first mentioned U-shaped lever, and a shackle connecting the opposite 55 end of the second lever to the supporting member.
15. In a sheaf shocker and in combination, a roller supported member mounted with freedom to tilt about a transverse axis and to move forwardly and rearwardly, a collapsible basket formed of a plurality of hinged sections adapted to normally open on the 60 upperside to receive the sheaves discharged therein and operatively connected to the supporting member, means supporting the basket in open position adapted when released to permit the sections to close about the sheaves to form a shock, means to move the supporting member forwardly and rearwardly and means for counter-balancing the weight on the forward and rear portions of the supporting member.
16. In a sheaf shocker and in combination, a transverse axis, a supporting member mounted with freedom to tilt about the transverse axis and to move forwardly and rearwardly, a collapsible basket formed with a plurality of hinged sections adapted to normally open on the upper side to receive the sheaves discharged therein and operatively connected to the supporting member, means supporting the basket in open position adapted when released to permit the sections to close about the sheaves to form a shock, means for moving the supporting member forwardly and rearwardly, means for counter-balancing the weight on the forward and rear portions of the supporting member, the said last mentioned means including a frame, a pulley on the frame, a cable extending over the pulley and springs connecting the opposite ends of the cable to the supporting member on opposite sides of the frame.
17. In a sheaf shocker and in combination, a collapsible basket formed of a plurality of hinged sections adapted to normally open on the upper side to receive the sheaves discharged therein, a cradle operatively supporting the basket with freedom to collapse about a shock, means supporting the basket in open position, adapted when released to permit the sections to close about the sheaves to form a shock, a trip device normally preventing turning of the cradle, the said cradle being adapted to turn when released and swing the basket into discharging position.

tion, a trip controlled mechanism adapted to be released and set in operation by the basket during collapsing to cause the turning of the cradle and lowering of the basket.

5 18. In a sheaf shocker and in combination a collapsible basket formed of a plurality of hinged sections, adapted to normally open on the upper side to receive the sheaves discharged therein, a cradle operatively supporting the basket with freedom to collapse about a shock, means supporting the basket in open position adapted when released to permit the sections to close about the sheaves to form a shock, a trip device normally preventing turning of the cradle, the said cradle being adapted to turn when released and swing the basket to discharging position, a trip controlled mechanism adapted to be released and set in operation by the basket 15 during collapsing to cause the turning of the cradle and lowering of the basket and a second trip mechanism also thrown into operation by the basket during its turning movement, adapted to cause the basket to be moved rearwardly prior to discharging of the shock.

19. In a sheaf shocker and in combination, a collapsible basket formed of a plurality of hinged sections adapted to normally open 30 on the upper side to receive the sheaves discharged therein, a cradle operatively supporting the basket with freedom to collapse about a shock, means supporting the basket in open position adapted when released to permit the sections to close about the sheaves to form a shock, a trip device normally preventing turning of the cradle, the said cradle being adapted to turn when released and swing the basket to discharging position, a trip controlled mechanism adapted to be released and set in operation by the basket 35 during collapsing to cause the turning of the cradle and lowering of the basket and a second trip mechanism also thrown into operation by the basket during its turning movement adapted to cause the basket to be moved rearwardly prior to discharging of a shock and means adapted to cause the basket to be dropped substantially vertically.

50 20. In a sheaf shocker and in combination, a supporting member, a cradle pivotally mounted in the supporting member adapted when free to turn into discharging position, a collapsible basket formed of a plurality of hinged sections adapted to normally open on the upper side to receive the sheaves discharged therein and operatively connected to the cradle, a trip lever normally preventing turning of the cradle, a trip arm carried by the basket, a trip mechanism adapted to be engaged by the trip arm and cam controlled mechanism set in operation by the trip adapted to close and lower the basket and move the basket rearwardly prior to 55 discharging.

21. In a sheaf shocker and in combination, a supporting member, a cradle pivotally mounted in the supporting member adapted when free to turn into discharging position, a collapsible basket formed of a plurality of hinged sections adapted to normally open on the upper side to receive the sheaves discharged therein and operatively connected to the cradle, a trip lever normally preventing turning of the cradle, a trip arm 70 carried by the basket, a trip mechanism adapted to be engaged by the trip arm and cam controlled mechanism set in operation by the trip adapted to close and lower the basket and move it rearwardly prior to discharging, a second trip arm carried by the basket and a second trip mechanism thrown into operation by the second trip arm adapted to cause turning of the basket.

22. In a sheaf shocker and in combination, 85 a power shaft, a cam on the power shaft, connecting means adapted to operatively connect the same with the power shaft, trip controlled mechanism adapted to throw the connecting means into operation, a supporting member, a cradle pivotally mounted in the supporting member adapted when free to turn into discharging position, a collapsible basket formed of a plurality of hinged sections adapted to normally open 90 on the upper side to receive the sheaves discharged therein and operatively carried by the cradle and means operated by the cradle in its turning movement for releasing the aforementioned trip mechanism.

23. In a sheaf shocker and in combination, 105 a power shaft, a cam on the power shaft, connecting means adapted to operatively connect the same with the power shaft, trip controlled mechanism adapted to throw into operation the connecting means, a supporting member, a cradle pivotally mounted in the supporting member adapted when free to turn into discharging position, a collapsible basket formed of a plurality of hinged sections adapted to normally open 110 on the upper side to receive the sheaves discharged therein and operatively carried by the cradle, means operated by the cradle in its turning movement for releasing the aforementioned trip mechanism and connecting means between the cam and the power shaft including a toothed disc and an arm connected to the cam and pivotally mounted on the power shaft, a pawl adapted to form a connection between the arm and the disc and a dog controlling the operation of the pawl.

24. In a sheaf shocker and in combination, 125 a power shaft, a cam on the power shaft, connecting means adapted to operatively connect the same with the power shaft, trip controlled mechanism adapted to throw the connecting means into operation, a supporting member, a cradle pivotally mounted in 130

position, the said mechanism being adapted to move the basket rearwardly prior to discharging.

31. In a sheaf shocker and in combination, a collapsible basket formed of a plurality of hinged sections adapted to normally open on the upper side to receive the sheaves discharged therein, a supporting member, a cradle pivotally mounted in the supporting member, adapted to turn about a transverse axis and operatively connected to the collapsible basket, means supporting the basket in open position adapted when released, to permit the basket to close about the sheaves to form a shock, trip controlled mechanism set in operation by the closing of the basket adapted to turn the cradle and lower the supporting member to open the basket and finally return it to its original position, a lever having its lower end movably pivoted and its upper end pivoted to the supporting member, and means for moving the lower end of the lever forwardly while the basket is being lowered.

32. In a sheaf shocker and in combination, a collapsible basket formed of a plurality of hinged sections adapted to normally open on the upper side to receive the sheaves discharged therein, a supporting member, a cradle pivotally mounted in the supporting member adapted to turn about a transverse axis and operatively connected to the collapsible basket, means supporting the basket in open position adapted when released, to permit the basket to close about the sheaves to form a shock, trip controlled mechanism set in operation by the closing of the basket adapted to turn the cradle and lower the supporting member to open the basket and finally return it to its original position, and removable means for preventing sheaves discharging through the end of the basket until the proper time.

33. In a sheaf shocker and in combination, a collapsible basket formed of a plurality of hinged sections adapted to normally open on the upper side to receive the sheaves discharged therein, a supporting member, a cradle pivotally mounted in the supporting member adapted to turn about a transverse axis and operatively connected to the collapsible basket, means supporting the basket in open position adapted when released, to permit the basket to close about the sheaves to form a shock, trip controlled mechanism set in operation by the closing of the basket adapted to turn the cradle and lower the supporting member to open the basket and finally return it to its original position, comprising pivotally mounted doors normally extending across the open end of the basket and adapted to be swung outwardly and upwardly prior to discharging of the shock.

34. In a sheaf shocker and in combina-

tion, a supporting member having a bifurcated end, a cradle pivotally mounted in the bifurcated end with freedom to turn about a transverse axis, a collapsible basket mounted in the cradle, means for operating the basket to close the same on a shock and to turn the cradle about a transverse axis, means for moving the supporting member forwardly and rearwardly and lowering the end of the same.

35. In a sheaf shocker and in combination, a supporting member having a bifurcated end, a cradle pivotally mounted in the bifurcated end with freedom to turn about a transverse axis, a collapsible basket mounted in the cradle, means for operating the basket to close the same on a shock and to turn the cradle about a transverse axis, means for moving the supporting member forwardly and rearwardly and lowering the end of the same, the last said mentioned means including a pair of levers having their ends pivoted together and one lever being connected to the supporting member, and a supporting frame connected to the opposite lever.

36. In a sheaf shocker and in combination, a supporting member having a bifurcated end, a cradle pivotally mounted in the bifurcated end with freedom to turn about a transverse axis, a collapsible basket mounted in the cradle, means for operating the basket to close the same on a shock and to turn the cradle about a transverse axis, means for moving the supporting member forwardly and rearwardly and lowering the end of the same, the last said mentioned means including a pair of levers having their ends pivoted together and one lever being connected to the supporting member, and a supporting frame connected to the opposite lever, a guide-way, a roller in the guide-way, means for connecting the roller to the opposite ends of the supporting member to that which is connected to the lever.

37. In a sheaf shocker and in combination, a supporting member having a bifurcated end, a cradle pivotally mounted in the bifurcated end with freedom to turn about a transverse axis, a collapsible basket mounted in the cradle, means for operating the basket to close the same on a shock and to turn the cradle about a transverse axis, means for moving the supporting member forwardly and rearwardly and lowering the end of the same, a frame, and guide members on the frame adapted to engage the bifurcated end of the supporting member.

38. In a sheaf shocker and in combination, a supporting member having a bifurcated end and a cradle mounted in the bifurcated end with freedom to turn about a transverse axis, a pair of links pivotally mounted on opposite sides of the cradle, a collapsible basket formed of a plurality of hinged sec-

tions, two of the sections being connected to the links, rods pivotally connected to the links, and having their free ends pivoted together, releasable means for preventing movement of the shaft ends away from the basket and means to engage the releasing means to cause the hinged sections of the basket to collapse about a shock.

39. In a sheaf shocker and in combination, 10 a shock forming basket formed of a plurality of hinged sections adapted to collapse on the shock, means for operating and closing the basket, means for turning, lowering and opening the basket and returning it to a 15 normal position, said basket adapted to receive the sheaves as they are discharged from the binder and to discharge them into a shock forming basket, and a transferring basket pivotally mounted with freedom to 20 swing about an axis inclined to a horizontal, adapted when in normal position to receive sheaves from the binder, and adapted when raised to discharge them into the shock forming member.
- 25 40. In a sheaf shocker and in combination, a transferring basket, a bracket supporting the same, means for pivotally mounting the basket on the bracket, means for turning the bracket, a fork adapted to retain the sheaves 30 of the transferring basket until the same is

raised to discharging position and then to release the same.

41. In a sheaf shocker and in combination, a transferring basket, a bracket supporting the same, means for pivotally mounting the 35 basket on the bracket, means for turning the bracket, a fork being adapted to retain the sheaves in the transferring basket until the same is raised to discharging position and then to release the same, and toggle mechanism 40 controlling the position of the fork.

42. In a sheaf shocker and in combination, a transferring basket, a bracket supporting the same, means for pivotally mounting the basket on the bracket, means for turning the 45 bracket, a fork adapted to retain the sheaves in the transferring basket until the same is raised to discharging position and then to release the same, and toggle mechanism controlling the position of the fork, the said 50 toggle mechanism including a pair of levers, the end of one of the levers being connected to the fork, and the other lever being pivotally mounted about the axis on which the basket turns, and an abutment member 55 adapted to engage the pivotal joint of the levers.

In witness whereof I have hereunto set my hand.

FREDERICK JAMES THODY.
